UNITED STATES PATENT OFFICE.

WILLIAM L. RUCKER, OF MARTINSVILLE, MISSOURI.

CORN-PLANTER.

SPECIFICATION forming part of Letters Patent No. 336,750, dated February 23, 1886.

Application filed September 8, 1885. Serial No. 176,522. (No model.)

To all whom it may concern:

Be it known that I, WILLIAM L. RUCKER, a citizen of the United States, and a resident of Martinsville, in the county of Harrison and State of Missouri, have invented certain new and useful Improvements in Corn-Planters; and I do hereby declare that the following is a full, clear, and exact description of the invention, which will enable others skilled in the art to 5 which it appertains to make and use the same, reference being had to the accompanying drawings, which form a part of this specification, and in which—

Figure 1 is a perspective view of my improved check-row corn-planter. Fig. 2 is a plan view of the same, and Fig. 3 is a perspective detail view of the drop mechanism.

Similar letters of reference indicate corresponding parts in all the figures. 20 My invention has relation to that class of check-row corn-planters in which a shaft is provided with hubs having spokes traveling upon the ground and thus revolving the shaft, and in which the said shaft by suitable cam mechanism reciprocates the seed-slides; and it consists in the improved construction and combination of parts of the same, as herein-after more fully described and claimed.

In the accompanying drawings, the letter A indicates the frame of the machine, which is mounted upon wheels B B, and which is provided with the runners C C, having the seed-boxes D D, mounted at their upper ends, the said seed-boxes having the transverse seed-slide E, sliding upon the frame. A transverse shaft or axle, F, is journaled in bearings G G at the lower ends of brackets H, secured near the runners, and the ends of this axle are provided with hubs I, having a number of radiating spokes, J, the ends of which will engage the ground as the machine travels over the same. The axle is provided with a cylinder, K, which has one or more lugs, L, projecting from its face, and a bolt, M, projects forward from the frame of the machine, and has a lever, N, pivoted upon its end, the upper end, O, of which lever is bent rearward, and fits into a staple, P, upon the upper side of the seed-slide, while the lower end of the lever is provided with a cam, Q, which is engaged by the lug upon the cylinder. The cam is curved so as to fit around the upper part of the cylinder,

and has its front end a trifle wider than where it is pivoted to the lever N, and has its rear end drawn out to a narrow strip. As the cylinder K revolves, the lug L will engage with the rear portion of the cam and force it to one side until the ends of the cam engage with the cylinder. As the cylinder continues to revolve, the cam is gradually forced to one side 55 until the lug passes the pivotal point, when it bears against the wider portion of the cam and forces it to swing on the pivot, thus throwing the rear portion of the cam in the opposite direction, so that at the next revolution the 60 lug will engage with the other side of the cam and force it over in the opposite direction. As the cam is moved alternately from side to side the rear end of the lever N is correspondingly moved back and forth and with it the seed-slide. One of the spokes, at the ends of the axle, is provided with a removable enlargement, S, which will mark the hills dropped, and consequently leave marks for commencing the next row when the machine has arrived to 65 the end of one row. The cylinder is provided with a ratchet-wheel, T, having the straight shoulders or faces of its teeth facing forward, and a pawl-arm, U, is pivoted at its rear end near the lower end of a hand-lever, V, which 70 is fulcrumed upon the frame near the seat W of the driver, and it will be seen that by rocking this hand-lever the downwardly-bent end X of the pawl-lever will engage the ratchet-teeth and revolve the cylinder backward, the 75 said mechanism being used when a new row is to be started and it is desired to drop a hill at a line with the hills formerly dropped. By increasing the number of lugs upon the cylinder the seed-slide may be continually reciprocated, converting the machine into a drill, and, 80 if desired, the hubs having the spokes at the ends of the axle may be dispensed with, and one hub having spokes may be secured near the middle of the cylinder. It also follows 85 that the spoked hubs may be dispensed with and other means resorted to, such as a grooved wheel having a check-rope passing around it, a hub having forked spokes having a rope passing around it, or any other suitable manner of revolving the axle, without departing 90 from the spirit of my invention.

This seed-slide-operating mechanism may be applied to any planter having a trans-

versely-reciprocating seed-slide, and the shape of the cam is such that it will suddenly throw the seed-slide to one side or the other in passing the wider portion of the cam, and this cam is pivoted upon the lower end of the lever so as to have sufficient play to allow the lug to pass at both sides of the cam, while the flanges of the rear flanged portion of the cam will bear against the edges of the lower end of the lever so as to prevent it from swinging or tilting so far out of the way of the lug that the lug will not rock the lever.

Having thus described my invention, I claim and desire to secure by Letters Patent of the 15 United States—

1. In a corn-planter, the combination of a revolving axle having a cylinder provided with a radially-projecting lug, with a lever pivoted upon the frame and having its upper 20 end connected to the seed-slide, and having its lower end provided with a curved cam pivoted upon the same, and having its forward end wider than where it is pivoted to said lever,

and the rear end narrow, as and for the purpose shown and set forth.

2. In a corn-planter, the combination, with a cylinder provided with a radiating lug, of a transversely-reciprocating seed-slide having a staple upon its upper side, a lever pivoted upon the front of the machine in the same vertical plane as the lug upon the cylinder, and having its upper end bent rearward and inserted into the staple upon the seed-slide, and a cam pivoted upon the lower end of the lever curved to correspond with the contour of the 35 cylinder, having its forward end wider than where it is pivoted to said lever, and having its rear end narrowed, as and for the purpose shown and set forth.

In testimony that I claim the foregoing as 40 my own I have hereunto affixed my signature in presence of two witnesses.

WILLIAM L. RUCKER.
